UNITED STATES PATENT OFFICE.

ARTHUR W. BURKS, OF DECATUR, ILLINOIS.

ROTARY PUMP.

Application filed January 10, 1925. Serial No. 1,678.

This invention relates to pumps, and more particularly to pumps of the rotary type, which comprises an impeller or rotor having a series of buckets opening within a substantially closed fluid raceway, the centrifugal force generated by the rotor serving to overcome the head against which the pump operates.

An object of the invention is to provide a pump rotor having an improved form of bucket construction, and to combine with the rotor a casing having a raceway so related to the rotor that it affords a substantially closed passage or channel for the fluid as it passes through the pump.

The invention also has as its object the provision of a multiple stage pump embodying a plurality of fluid raceways intercommunicating and adapted successively to receive the fluid, there being in association with each raceway a series of buckets serving to increase the velocity and pressure head of the fluid as the same passes through the several raceways successively.

In the accompanying drawings there are shown certain devices embodying the invention, and in these drawings:

Fig. 1 is a top plan view,

Fig. 2 is a cross section on the line 2—2 of Fig. 3,

Fig. 3 is a section on the line 3—3 of Fig. 2 looking in the direction of the arrows,

Fig. 4 is a view similar to Fig. 3 showing a single stage pump, and

Fig. 5 is a section on the line 5—5 of Fig. 4.

Referring to the drawings more in detail, and considering first the form of the device shown in Figs. 1, 2 and 3, 10 indicates a casing having a circumferential wall 10' provided on its inner face with a plurality of grooves or raceways 11, 12 and 13 arranged in substantially parallel planes and of substantially equal diameter. The grooves are suitably spaced apart by dividing walls and the groove 11 has an inlet opening 14 through which the fluid enters the casing, this groove serving as the first stage raceway. The circumferential wall of the casing is thickened at the upper portion thereof and a passage way 15 serves to permit the fluid to pass through an outlet opening 14' from the raceway 11 to the raceway 12, which it enters through an inlet 12'. The latter mentioned raceway communicates through an outlet 12'' with a passage 16 connecting the same

with the inlet opening 13' of the raceway 13, the latter having a pump outlet opening 17 (Fig. 1).

By reference to Fig. 1 it will be observed that the raceway 12 has its inlet opening 12', and the raceway 13 its inlet opening 13' in alignment with the pump inlet 14, and the outlet 12'' of the raceway 12 as well as the outlet 14' of the first stage raceway 11 are aligned with the pump outlet 17. The arrangement of the inlet and outlet openings of the raceways in the same relative positions with respect to the rotor insures that in each raceway the fluid will be treated in substantially the same manner and without impeding the progress of the fluid through the pump. The raceways do not extend completely around the wall of the casing, but are closed between the inlet and outlet openings at the top of the casing, as will be noted in Fig. 3, in order to prevent leakage of the water or other fluid past the outlet openings.

A shaft 18 extends through the casing, having a bearing 19 in a boss 20, and a bearing 21 in a face plate 22 secured to the casing as by bolts 23. A gland 24 serves to close a stuffing box 26 in which is located suitable packing to seal the casing against leakage.

Upon the shaft 18 is fixedly mounted a rotor, in the present instance formed of a plurality of sections 26, 27 and 28 which cooperate, respectively, with the raceways 11, 12 and 13. Each rotor section has a peripheral groove or channel 29 and its periphery on opposite sides of the channel makes a close and substantially water-tight joint with the wall of the casing. Thus, each peripheral rotor groove and the surrounding raceway of the casing form, together, a substantially closed passage for the fluid in which the fluid is operated upon by impelling means on the rotor. In each rotor groove 29 there is positioned a series of blades 30 extending transversely of the groove and inclined in the direction of rotation of the rotor, as indicated by the arrow in Fig. 3. The inclination of the buckets materially minimizes the force of the impact of the fluid entering each raceway through its inlet opening, and the ends of the blades are substantially flush with the periphery of the rotor, thus affording a clear and unobstructed raceway. While the rotor is shown in the drawings as being formed of separate members, it will be understood that the use of an integral struc-

ture is within the scope of the invention, it merely being necessary for the accomplishment of the objects of the invention that the series of buckets and raceways be separated 5 substantially in the manner indicated.

In the operation of the pump, fluid enters the raceway 11 through the inlet opening 14 and is engaged by the buckets of the impeller 11 which carry the fluid around the 10 raceway to the outlet 14'. During its course through the raceway the fluid is repeatedly engaged by the buckets and its velocity head is materially increased by the action of the centrifugal force which tends to throw the 15 water against the outer wall of the raceway, the centrifugal force being modified by forward or tangential force created by the revolution of the rotor. The path actually taken by the fluid is a component of these 20 two forces. Each amount of fluid operated upon in this manner obtains a great increase in velocity head, which is immediately imparted in the form of pressure head to the advance or preceding fluid in the raceway. 25 After the fluid has been thus actuated in the first stage raceway 11 it travels through the outlet opening 14' thereof and the passageway 15 to the second stage raceway 12, entering the latter through the inlet 12' 30 where it is at once engaged by the buckets of the rotor 27. After following the course of the second stage raceway 12 the fluid passes through the outlet 12'' and passageway 16 to the final raceway 13, wherein it 35 is operated upon by the rotor 28 and forced through the pump outlet opening 15.

Referring to the structure shown in Figs. 4 and 5, my improved rotor is shown as embodied in a single stage pump. 34 indicates 40 a casing having a peripheral wall 35 provided with an inlet opening 36 which communicates with a channel 37 serving as a raceway. The raceway is of circular formation and extends around the inner face of 45 the casing wall to an outlet opening 38, the raceway terminating at a deflecting wall 39 which fits closely the ends of the blades and periphery of the impeller to prevent leakage of the fluid in any substantial volume 50 past the outlet opening 38. A rotor 40 is positioned upon a shaft 41 which has bearings 42 and 43, the latter bearing being in a cover plate 44 secured to the casing as by bolts 45. The rotor is formed with a 55 peripheral channel 46 and fits closely against the wall 35 of the casing on each side of the channel, in which are positioned blades 47 forming a series of peripheral buckets; the blades are substantially flush with the 60 periphery of the rotor on each side of the channel 46 and are suitably aligned with the raceway. The pump operates in substantially the same manner as the form shown in Figs. 1, 2 and 3, but the fluid, 65 after passing through the single raceway,

immediately makes its exit through the outlet opening without passing through further stages of pump actuation.

It will be observed that in both the multiple and single stage pumps, the raceways 70 are curved, and more specifically, of substantially semi-circular formation in cross-section. Moreover, the walls of the raceway and buckets merge or are substantially continuous at the lines of juncture, and the 75 cross-sectional shape of each bucket is such that in association with the adjacent cross-section of the raceway, the entire wall of the bucket and raceway is of curved or circular form, as will be noted particularly in 80 Figures 2 and 5. This construction avoids any sharp corners or bends for the water, and when the same is thrown upwardly by a centrifugal action, a whirling effect is 85 imparted thereto by the raceway, and it returns to the buckets at a point further on in the raceway without such loss by friction as would occur if the buckets were not associated as above described.

It should be understood that numerous 90 modifications may be made in the structure illustrated and described without departing from the scope of the invention, which is more definitely defined in the following 95 claims.

I claim:

1. A pump comprising a rotor having on its periphery an annular channel or groove, a plurality of blades each extending transversely of said groove to form a series of 100 buckets, the ends of said blades being substantially flush with the periphery of the rotor on each side of said groove, and a casing having an annular channel therein surrounding said series of buckets, said casing on each 105 side of the channel making a substantially water-tight joint with the periphery of the rotor to form a closed fluid raceway and having inlet and outlet openings and means interposed therebetween to closely fit the exposed edges of the blades and periphery of the impeller to deflect liquid from the raceway to the outlet.

2. A pump comprising a rotor having on its periphery an annular channel or groove, 115 a plurality of blades each extending transversely of said groove to form a series of buckets, and a casing having an annular channel therein surrounding said series of buckets, said casing on each side of the channel making a water-tight joint with the periphery of the rotor to form a closed fluid raceway and having inlet and outlet openings and means interposed therebetween to closely fit the exposed edges of the blades 120 and periphery of the impeller to deflect liquid from the raceway to the outlet.

3. A pump comprising a rotor having on its periphery an annular channel or groove, a plurality of blades each extending trans- 130

versely of said groove to form a series of buckets, and being inclined in the direction of rotation of the rotor, the ends of said blades being substantially flush with the periphery of the rotor on each side of said groove, and a casing having an annular channel therein surrounding said series of buckets, said casing on each side of the channel making a substantially water-tight joint 10 with the periphery of the rotor to form a closed fluid raceway and having inlet and outlet openings and means interposed therebetween to closely fit the exposed edges of the blades and periphery of the impeller to 15 deflect liquid from the raceway to the outlet.

4. A pump comprising a rotor having on its periphery an annular channel or groove, a plurality of blades each extending transversely of said groove to form a series of buckets, and being inclined in the direction of rotation of the rotor, and a casing having an annular channel therein surrounding said series of buckets, said casing on each 20 side of the channel making a substantially water-tight joint with the periphery of the rotor to form a closed fluid raceway and having inlet and outlet openings and means interposed therebetween to closely fit the exposed edges of the blades and periphery of the impeller to deflect liquid from the raceway to the outlet.

5. In a multiple stage rotary pump, a casing having a plurality of communicating raceways arranged in substantially parallel planes, and a rotor in the casing having a plurality of series of buckets, each series being surrounded by a raceway and the casing making substantially water-tight joints with 35 the rotor between the series to form closed fluid raceways and having inlet and outlet openings and means interposed therebetween to closely fit the exposed edges of the blades and periphery of the impeller to deflect liquid from the raceway to the outlet.

6. In a multiple stage rotary pump, a casing having a plurality of raceways arranged in substantially parallel planes and a passage connecting said raceways, and a rotor in 50 said casing having a plurality of series of buckets with each series surrounded by a raceway, the casing making substantially water-tight joints with the rotor at the sides of each series to form closed fluid raceways and having inlet and outlet openings and means interposed therebetween to closely fit the exposed edges of the blades and periphery of the impeller to deflect liquid from the raceway to the outlet.

60 7. In a multiple stage rotary pump, a casing having a plurality of raceways of substantially equal diameter, a passage connecting said raceways, an inlet opening communicating with one raceway, and an outlet opening communicating with another of said

raceways; a rotor in said casing having a plurality of series of buckets, each series of buckets being surrounded by a raceway and the casing making substantially water-tight joints with the rotor to form closed fluid 70 raceways.

8. In a multiple stage rotary pump, a casing having a plurality of communicating raceways, an inlet opening communicating with one raceway, and an outlet opening 75 communicating with another of said raceways; a rotor in said casing having a plurality of series of peripheral buckets, each series being surrounded by a raceway and the casing making substantially water-tight 80 joints with the rotor to form closed fluid raceways.

9. In a multiple stage rotary pump, a casing having a plurality of communicating raceways, an inlet opening communicating 85 with one raceway, and an outlet opening communicating with another of said raceways; a rotor in said casing having a plurality of series of peripheral buckets, each series being surrounded by a raceway and 90 the casing making substantially water-tight joints with the periphery of the rotor to form closed fluid raceways, said casing having adjacent said outlet opening means closely fitting the periphery of the rotor and the 95 exposed edges of the blades to deflect liquid to the outlet.

10. In a multiple stage rotary pump, a casing having a plurality of communicating raceways, an inlet opening communicating 100 with one of said raceways and an outlet opening communicating with another of said raceways; a rotor in the casing having spaced peripheral grooves, and a plurality of blades in each groove extending transversely thereof to form a series of buckets, said casing making substantially watertight joints with the periphery of the rotor at the sides of the series of buckets to form closed fluid raceways and having adjacent said outlet opening 105 means closely fitting the exposed edges of the blades and the periphery of the rotor to deflect liquid to the outlet.

11. In a multiple stage rotary pump, a casing having a plurality of communicating raceways, an inlet opening communicating with one of said raceways and an outlet opening communicating with another of said raceways, a rotor in the casing having spaced peripheral grooves, and a plurality of blades in each groove extending transversely thereof to form a series of buckets, the ends of 115 said blades being substantially flush with the periphery of the rotor on each side of said groove, and said casing making substantially water-tight joints with the periphery of the rotor at the sides of the series of buckets to form closed fluid raceways.

12. In a multiple stage rotary pump, a casing having a plurality of communicating 120

raceways, an inlet opening communicating with one of said raceways and an outlet opening communicating with another of said raceways; a rotor in said casing having peripheral grooves, each groove being surrounded by a raceway, and a plurality of blades in each groove extending transversely of the groove to form a series of buckets, the blades being inclined in the direction of rotation of the rotor and the casing making substantially water-tight joints with the rotor at the sides of the buckets to form closed fluid raceways.

13. In a multiple stage rotary pump, a casing having a plurality of communicating raceways, an inlet opening communicating

with one of said raceways and an outlet opening communicating with another of said raceways, a rotor in said casing having peripheral grooves, each groove being surrounded by a raceway, and a plurality of blades in each groove extending transversely thereof to form a series of buckets, the blades being inclined in the direction of rotation of the rotor, and the casing making substantially water-tight joints with the periphery of the rotor at the sides of each series of buckets to form closed fluid raceways. 20 25

In testimony whereof I have hereunto set my hand.

ARTHUR W. BURKS.
